(57) **CLAIM**

The ornamental design for a notched medical dressing, as shown and described.

DESCRIPTION

FIG. 1 is a perspective view of a notched medical dressing showing the new design;

FIG. 2 is a top view thereof;

FIG. 3 is a bottom view thereof;

FIG. 4 is a front view thereof;

FIG. 5 is a back view thereof; and,

FIG. 6 is a side view thereof, the opposing side view being identical.

The broken lines in FIGS. 1-6 are for illustrative purposes only and form no part of the claimed design.
